UNITED STATES PATENT OFFICE.

FRANK E. HALLADAY, OF PLOVER, WISCONSIN.

GUN-SIGHT.

SPECIFICATION forming part of Letters Patent No. 353,786, dated December 7, 1886.

Application filed April 23, 1886. Serial No. 199,882. (No model.)

To all whom it may concern:

Be it known that I, FRANK E. HALLADAY, a citizen of the United States, residing at Plover, in the county of Portage and State of Wisconsin, have invented certain new and useful Improvements in Gun-Sights, of which the following is a full, clear, and exact description, reference being had to the accompanying drawings, forming part of this specification, in ⁵ which—

Figure 1 represents a perspective view of a gun-sight embodying my improvements. Fig. 2 is a longitudinal sectional view of the same.

My invention relates to sights for fire-arms; ¹⁵ and it comprises a spring-plate, a horizontal screw, and wedge-shaped block for adjusting the sight, as I shall hereinafter fully describe and claim.

To enable others skilled in the art to make ²⁰ and use my invention, I will now describe its construction and the manner in which it is carried out.

In the said drawings, A represents a portion of a gun-barrel on which the sight is secured, ²⁵ provided with a dovetailed slot, a, in which is fitted to be adjusted laterally the dovetailed head b of the leaf B. This leaf is simply a spring-plate firmly held to its engagement with the barrel A by reason of the dovetailed ³⁰ connection before described, and having at its front the projection b', provided with the usual sight-notch, b", as shown in Fig. 1.

The forward end of the plate B is cut away to form the slot c, within which slides and is ³⁵ guided an inclined or wedge-shaped block, D, having lugs d d', resting upon the upper surface of the barrel. The lug d' is provided with a threaded perforation, through which passes one end of the horizontal screw E, the opposite end of said screw being secured in a rotating nut, e, journaled within a slot, f, formed in the head b of the plate B, as shown.

From this description it is manifest the movement of the screw and rotating nut in either ⁴⁰ direction will cause the wedge shaped block to advance or recede. As said block passes beneath the projecting portion b' of the plate or

leaf B, it is evident said projection and plate may be forced upward or lowered, as the circumstances require. Therefore I am enabled ⁵⁰ to obtain a minute adjustment of the sight, which, when once adjusted, is not affected by light winds, head or rear winds, nor by varying charges of powder, which require a change of elevation or depression, and which ⁵⁵ in other sights often so modify the previous adjustment as to seriously affect the result of the shooting. I am also enabled to obtain elevation for any distance where a spring-sight is used. The sight may also be instantly ⁶⁰ changed, does not require watching, is readily operated, and is adapted for all sizes and calibers of guns, and for light or heavy charges of powder.

Having thus described my invention, what I ⁶⁵ claim as new, and desire to secure by Letters Patent, is—

1. An improved sight for fire-arms, comprising a spring-plate, B, a block, D, sliding upon the barrel and having an inclined face engaging ⁷⁰ said plate, and a screw engaging the block, whereby the sight is adjusted.

2. The combination, with the spring-plate B, one end of which is secured in a slot formed in the barrel, of an inclined or wedge-shaped ⁷⁵ block sliding upon said barrel, and adjusting the spring-plate, and a screw and nut for moving the block, substantially as herein described.

3. The combination, with the barrel of a gun ⁸⁰ provided with a dovetailed slot, of the plate B, having a head fitting within the slot, a slotted forward portion, and a projection, b, a sliding block having an inclined upper face engaging the plate B, a horizontal screw mounted ⁸⁵ in said plate and engaging a threaded aperture in the sliding block, and an operating-nut secured to the screw, substantially as herein described.

FRANK E. HALLADAY.
